UNITED STATES PATENT OFFICE.

PEDRO SORRIGUETA, OF BILBAO, SPAIN.

GAS ENGINE.

Application filed June 8, 1918. Serial No. 238,972.

To all whom it may concern:

Be it known that I, PEDRO SORRIGUETA, a subject of the King of Spain, residing at Bilbao, in the Province of Vizcaya, Spain, **5** have invented certain new and useful Improvements in Gas Engines, of which the following is a specification.

This invention relates to internal combustion or gas engines and more particularly **10** to the two-cycle opposed cylinder type of engine particularly adapted for use on aeroplanes, although it is, of course to be understood that many of the features are applicable to other uses.

15 One of the objects of the present invention is to provide a simple and practicable gas engine of the above general type capable of high efficiency.

A further object is to provide an engine **20** of the above general character adapted to give the high speed and high power necessary for aeroplane use and at the same time be relatively light in weight, yet durable and fully capable of withstanding the strains to **25** which it is subjected.

Other objects will be in part obvious from the annexed drawings and in part indicated in connection therewith by the following analysis of this invention.

30 This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the numerous modifications in structure and **40** relation contemplated by this invention, drawings depicting a preferred form have been annexed as a part of this disclosure, and in such drawings, like characters of reference denote corresponding parts throughout **45** all the views, of which:—

Figure 1 is a partial transverse section and partial end view of such parts of the engine as are necessary to fully understand its construction and operation.

50 Figure 2 is a partial plan view and horizontal sectional view of one of the units of which the engine is composed taken sub-

stantially on line 2—2, Figure 1, but with parts in plan view.

Figure 3 is a side elevation of the complete **55** engine.

Referring now to the drawings in detail and more particularly to Fig. 3, 5 denotes the engine frame from each side of which extends a plurality of cylinders 6, in the **60** present case four, on each side of the crank case. These cylinders are provided with pistons 7 connected by means of piston rod 8 with a central longitudinally disposed crank shaft 10. This shaft is, of course, provided with eight turns or elbows and the piston rods 8 of each transverse pair of cylinders are connected therewith at substantially **65** 180°. It will also be noted on reference to Fig. 2, that the cylinders of **70** each pair are slightly offset with respect to each other permitting the piston rods 8 to be connected with the shaft 10 in a straight line, thereby avoiding a loss of efficiency due to a bent or angularly disposed piston. **75**

Positioned above the crank case and preferably forming a part thereof is an auxiliary cam shaft case 11 provided with a shaft **80** 12 carrying cams 13 and 14, Fig. 2, for actuating the intake and exhaust valves of the cylinders at the proper time. This shaft is rotated by means of a train of gears 15, 16 and 17 connected with the main crank shaft 10.

A magneto is indicated at 18 which is **85** connected with spark plugs 20 in any desired manner. Suitable water and lubricating pumps, not shown, are provided as may be necessary for securing the proper cooling of **90** the cylinders and lubrication of the movable parts. These, however, form no special part of the present invention and for clearness, their disclosure has been omitted.

For the sake of lightness, the main crank casing 5 and associated parts are made of **95** aluminum, and as indicated in Fig. 2, said casing is divided transversely into sections or units of two cylinders each to provide a small compact compression chamber, that is, the interior of the crank case, for the **100** opposed cylinders.

These cylinders are partially constituted by the crank case, while the remaining portion 21 is of copper surrounded by a steel

water jacket 22, the space between constituting a water chamber which is connected by means of nipples 23 with any suitable form of circulating system. Copper is particularly adapted for construction of this kind owing to the ease and rapidity with which it radiates the heat generated by the explosive mixture.

The inner end of each cylinder is provided with oppositely disposed tubes or passageways 24 communicating with the interior of the crank case and the interior of the cylinder when the piston is on its end stroke as shown at the left of Fig. 1. This piston is preferably made of two parts, that is, the piston head 7 and an auxiliary guide member 25 riveted thereto. The usual transverse pin 30 is provided to form one support of the piston rod 8, the opposite end of which is connected with the crank shaft 10. This rod may also be made of aluminum and relatively large in order to reduce the space in the compression chamber. A deflector 31 is provided at one side on the head of the piston for directing the inrushing compressed charge towards the head of the cylinder thereby to eject more efficiently the products of combustion of the previous charge. These exhaust gases are forced past a valve 32 which is actuated or opened by mechanism actuated by the cam 14.

This mechanism comprises a rod 33 having a roller engagement with the cam, said rod being mounted in a suitable bearing and having a universal connection 35 with the diagonally disposed rod 36 connected at its opposite end with rocker arm 37 pivoted on stud 38. The opposite end of this rocker arm engages the stem 40 of the valve 32 and urges the stem inwardly against the action of spiral spring 41. The products of combustion after passing through the valve 32 are conducted to the exhaust muffler, not shown, through a pipe 42 leading from each cylinder head.

The same cam shaft 12 is provided also with a plurality of cams 13 each adapted to actuate a rod 43 through roller contact, the rod passing through a bearing 44 and connected at its free end with a rocker arm 45 pivoted on a boss at 46. The opposite end of this rocker arm 45 coacts with a stem 47 of a valve 48 normally held in closed position by means of spring 50 within the compression chamber. This valve 48 is adapted to close the inlet to the crank case from any suitable source of supply, indicated by the intake manifold 51, which in turn communicates with pipes 52, as shown in Fig. 3 of the drawing.

The operation of the engine is substantially as follows:

Assuming the engine to be in position shown in Fig. 1, the previously compressed charge of gas in the crank casing passes

through the passageways or ports 24 into the interior or head of the cylinder where it drives out the previous products of combustion through the open valve 32. As the shaft 10 rotates the piston will move outwardly to further compress this charge of gas and on the completion of the stroke the charge will be ignited by means of spark plug 20 to again return the piston to the position shown in this figure. In the meantime, however, the gearing between the main crank shaft 10 and cam shaft 12 will have rotated the latter to bring the cams 13 and 14 into such proper relative position as to close the exhaust valve and open the inlet valve 48 at the proper time to allow a further supply of the combustible mixture to pass into the crank case for compression on the working stroke of the piston.

It will thus be seen that the present invention provides a simple and practicable two-cycle opposed cylinder engine particularly adapted for aeroplane use owing to its simplicity of construction, lightness of material and compact arrangement of working parts.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the following claims.

I claim:

1. In a gas engine, the combination of a pair of opposed cylinders; a central crank shaft; pistons in the cylinders connected by piston rods with said shaft; a crank case enclosing said shaft and piston rods and forming a compression chamber, the wall of each cylinder having passages which lead into the cylinder from said chamber and the outlet ends of which are covered and uncovered by the respective piston during its movements; an exhaust valve in the head of each cylinder; a single inlet valve for both cylinders associated with said chamber; and operating cams for said valves.

2. In a gas engine, the combination of a pair of opposed cylinders; a central crank shaft; pistons in the cylinders connected by piston rods with said shaft; a crank case enclosing said shaft and piston rods and forming a compression chamber which is in piston-controlled, port communication with both cylinders; an exhaust valve for each cylinder; a single inlet valve for both cylinders associated with said chamber; and operating cams for said valves.

3. In a gas engine, the combination of a

pair of opposed cylinders; a central crank shaft; pistons in the cylinders connected by piston rods with said shaft; a crank case enclosing said shaft and piston rods and forming a compression chamber which is in piston-controlled, port communication with both cylinders; an exhaust valve for each cylinder; a single inlet valve for both cylinders associated with said chamber; and oper-

ating cams for said valves mounted on a common support which is driven by said shaft.

In testimony whereof I affix my signature in the presence of two witnesses.

PEDRO SORRIGUETA.
